We claim the design for a platformed bicycle carrier rack, as shown and described.

DESCRIPTION

FIG. 1 is a perspective view of a platformed bicycle carrier rack;

FIG. 2 is left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.
